UNITED STATES PATENT OFFICE.

WILLIAM M. SCHOLL, OF CHICAGO, ILLINOIS.

ARCH-SUPPORT.

1,258,363.

Specification of Letters Patent.

Patented Mar. 5, 1918.

Application filed June 23, 1916. Serial No. 105,342.

To all whom it may concern:

Be it known that I, WILLIAM M. SCHOLL, a citizen of the United States, residing at Chicago, in the county of Cook and State of Illinois, have invented certain new and useful Improvements in Arch-Supports, of which the following is a specification.

My invention relates to improvements in instep arch supports, and has for its general object to provide an arch support useful in overcoming incorrect foot conditions, and improper walking habits, that result in a tendency to rotate the foot outwardly.

I have found that in many instances where foot treatment and the use of arch supporting appliances are necessary for the comfort of the wearer, the primary cause of the trouble resides in the incorrect application of the weight with respect to the bony and ligamentitious structure of the foot, and the effect is noticeable especially in a tendency upon the part of the patient to rotate the foot outwardly in walking. The arch support of my present invention effects its supporting functions fundamentally with respect to the outer edge of the foot, for correction of such ailments; and in the drawings wherein I have illustrated an embodiment of my invention.

Figure 1 is an inverted plan view of an arch support; showing in general fashion its intended relation to the foot structure illustrated in dotted lines;

Fig. 2 is a perspective view of the metal plate detached.

Fig. 3 is an end elevation from the anterior end of the plate detached; and

Figs. 4, 5 and 6 are sections respectively on line 4—4, 5—5 and 6—6 of the plate.

In accordance with my invention I provide as a main element of the arch supporting structure a relatively stiff metal plate 10 that has its outer edge 11 swung out as at 11^a beyond the relatively narrow heel 10^a so as to extend laterally beyond the cuboid bone and the posterior portion of the fifth metatarsal, the outer portion of the plate arched longitudinally as at 12, to an extent usually somewhat greater than the curvature of the foot with which the support is to be used at the proximate plantar sur-

faces. The extreme outer edge 11 is preferably up-turned somewhat as indicated at 11^a, Fig. 3, from the heel-ward portion of the arch 12 to the anterior end, 13, that preferably lies somewhat in rear of the metatarsophalangeal articulations. Such upturned edge, merging smoothly into the arched outer portion 12, gives to the foot an anchorage against outward displacement and at the same time strengthens somewhat the weight-carrying outer border portion of the plate. At a position corresponding with the posterior end of the fifth metatarsal the plate is preferably recessed, as shown at 15, so that no excessive pressure is thrown on that process.

To carry the corrective action well forward and afford especial support to the fourth and fifth metatarsals in rear of their heads, I preferably provide in the plate a diagonal slope 16, the outer edge of which is high but sloping off toward the central anterior portion of the plate, while the inner anterior portion preferably is cut away, as at 17, to afford a relief space to receive the head of the first metatarsal. This formation mechanically tilts the foot inward somewhat adjacent the ball of the foot, tending to throw the weight toward the first metatarsal head, which has ample clearance, and yet is prevented from shifting over inwardly by the conformation of the inner waist-portion of the plate.

Along its inner edge 2—, the plate is preferably shaped to leave free from direct support the inner portion of the scaphoid and first cuneiform bones (although extension beyond the indicated lines is desirable in some instances) so that the inner border of the plate is in-curved somewhat. In longitudinal section the plate is arched along its inner edge in measurable conformity to or slightly less than the curvature of the foot with which the support is to be used, so that, as indicated in Fig. 3, at the top of its longitudinal arch, the plate slopes from both edges 20 and toward the center of the plate; its elevation at the outer edge being in excess of the curvature of the foot with which the support is to be used and its elevation at the inner edge being not greater than the

- curvature of the foot with which the support is to be used. The foot is thus given a distinct tendency to rotate inward, which tendency is not excessive because it is balanced 5 in part by the resistance to extreme inward rotation and to lateral displacement that is offered by the inner arched portion. The difficulty in describing the magnitude of the plate curvature will be apparent, but by 10 starting with the understanding that a plate shaped to conform to the substantially normal or anatomically correct curvature of the arch of a foot would have no effect in correcting this tendency to outward rotation of 15 the foot, it will be appreciated that a curvature of the outer edge of the plate in excess of this normal or natural curvature will raise the outer side of the arch and tend to rotate the foot in the opposite direction. 20 A usual cover piece 25 secured to the plate by rivets 26 may be provided to aid in holding the plate in predetermined relation to the shoe and to give comfort to the wearer, if desired. 25 While I have herein described in some detail a specific structure embodying my invention for purposes of full disclosure, it will be understood that many changes in details may be made without departure from 30 the spirit of my invention within the scope of the appended claims.
- Having described my invention, what I claim is:—
1. An arch support, having its outer edge arched longitudinally in excess of the curvature of the foot with which the support is to be used and its inner edge arched in approximate conformity to the curvature of the foot with which the support is to be used. 35
  2. An arch support, having its outer edge arched longitudinally in excess of the curvature of the foot with which the support is to be used and its inner edge arched in approximate conformity to the curvature of the foot with which the support is to be used, the plate being transversely concaved at its waist portion. 45
  3. An arch support plate constructed to 50 extend from a bearing portion beneath the wearer's heel to approximately the metatarsal heads, laterally extended at its outer edge beyond the areas of the cuboid and fifth metatarsal bones, and upturned along said edge, said edge portion of the plate being arched longitudinally in excess of the curvature of the foot with which the support is to be used to tend to rotate the foot inwardly.
  4. An arch support plate constructed to 55 extend from a bearing portion beneath the wearer's heel to approximately the metatarsal heads, laterally extended at its outer edge

beyond the areas of the cuboid and fifth metatarsal bones, and upturned along said edge, said edge portion of the plate being arched longitudinally in excess of the curvature of the foot with which the support is to be used to tend to rotate the foot inwardly, and said arched portion recessed in 70 a position to receive the posterior part of the fifth-metatarsal.

5. An arch support plate constructed to extend from a bearing portion beneath the wearer's heel to approximately the metatarsal heads, laterally extended at its outer edge beyond the areas of the cuboid and fifth metatarsal bones, and upturned along said edge, said edge portion of the plate being arched longitudinally in excess of the curvature of the foot with which the support is to be used to tend to rotate the foot inwardly and said plate incurved along its inner edge and arched in not to exceed conformity with the curvature of the foot with 85 which the support is to be used.

6. An arch support plate constructed to extend from a bearing portion beneath the wearer's heel to approximately the metatarsal heads, laterally extended at its outer edge 90 beyond the areas of the cuboid and fifth metatarsal bones, and upturned along said edge, said edges portion of the plate being arched longitudinally in excess of the curvature of the foot with which the support is 95 to be used to tend to rotate the foot inwardly and said plate arched along its inner edge and cut away at its anterior end to receive the head of the first metatarsal.

7. An arch plate having its outer edge 100 arched in excess of the curvature of the foot with which the support is to be used and its anterior portion sloped laterally from its outer toward its inner edge.

8. An arch support providing means to 105 receive the heel, means to afford support to the highest arched portion of the foot inwardly from the longitudinal axis of the foot, and means arched in excess of the curvature of the foot with which the support is to be used to support the outer edge of the foot.

9. An arch support providing means to receive the heel, means to afford support to the highest arched portion of the foot inwardly from the longitudinal axis of the foot, and means arched in excess of the curvature of the foot with which the support is to be used to support the outer edge of the foot and means to coact with the 110 outer edge of the foot to prevent outward displacement of the foot.

10. An arch support providing means to receive the heel, means to afford support to the highest arched portion of the foot inwardly from the longitudinal axis of the 115

foot, and means arched in excess of the curvature of the foot with which the support is to be used to support the outer edge of the foot and means adjacent the anterior portion of the fourth and fifth metatarsals to rotate the foot inwardly.

In testimony whereof I hereunto set my

hand in the presence of two subscribing witnesses.

WILLIAM M. SCHOLL.
